UNITED STATES PATENT OFFICE.

ARTHUR C. STUART, OF CLEVELAND, OHIO, ASSIGNOR, BY MESNE ASSIGNMENTS, TO
JAMES R. GARFIELD, TRUSTEE, OF CLEVELAND, OHIO.

TELEPHONE-EXCHANGE SYSTEM.

1,384,980.

Specification of Letters Patent. Patented July 19, 1921.

Application filed November 11, 1912, Serial No. 730,752. Renewed May 3, 1921. Serial No. 466,530.

To all whom it may concern:

Be it known that I, ARTHUR C. STUART, a citizen of the United States, and resident of Cleveland, Cuyahoga county, State of Ohio, have invented certain new and useful Improvements in Telephone-Exchange Systems, of which the following is a specification.

My invention relates to telephone exchange systems, and especially to that class known as semi-automatic systems.

In systems of this class automatic switching mechanism controlled by operators is used in establishing connections between subscribers.

The object of my invention is to provide improved means in trunking from a manual switchboard to a semi-automatic exchange whereby simultaneous calls from the manual exchange can be controlled without interference or loss of time.

Further objects of my invention provide improved means for releasing the selector and connector switches used at the semi-automatic exchange for establishing connections.

A further object of this invention is to provide improved means in the connector circuit for flashing a signal at the operator's position to notify the operator that the called line is busy.

In the present instance I have shown the method of trunking from a manual switchboard to a semi-automatic exchange. The operator at the magneto board receiving a call from a subscriber, places the calling plug into a trunk jack which terminates at the semi-automatic exchange in a first selector switch. As soon as this connection is effected, the first selector switch and associated switches are controlled by the operator at the semi-automatic exchange who is provided with a suitable sending device.

After the connection is entirely established, the operator at the semi-automatic exchange is automatically disconnected from the main trunk and the switches are thereafter controlled by the operator at the magneto exchange or toll board. This operator is provided with suitable means for supervising the connections.

My invention is illustrated in the accompanying drawings wherein,

Figure 1 shows a cord circuit and a por-

tion of a trunk circuit terminating in a jack 55 at the manual switch board.

Fig. 2 shows the continuation of the trunk circuit at the semi-automatic exchange terminating in a first selector switch.

Fig. 3 shows a second selector circuit. 60

Fig. 4 shows a connector circuit with a party line selecting switch.

Fig. 5 shows a subscriber's line and control circuit at the semi-automatic exchange.

Figs. 6 and 7 show the control circuits 65 for the trunk and operator's key-set switch.

Fig. 8 shows the operator's key-set and controlling circuit.

Fig. 9 shows the operator's key-board and sending device. 70

Fig. 10 shows the manner in which the various figures are to be arranged.

Referring now to Fig. 1, the answering plug P^2 and the calling plug P^1 are joined together by the conductors indicated in 75 heavy lines for conversational purposes. These conductors are joined together through the contacts of keys 417, 416, 425 and 430. When the key 417 is operated, the operator's telephone set is connected to the 80 tip and sleeve conductors. When the key 416 is operated, generator is connected to the plug P^2 . When the key 425 is operated, the generator is connected to the plug P^1 . When the key 430 is operated, the repeating coil 420 and condenser 495 are inserted 85 between the talking conductors of the plugs P^1 and P^2 .

When the plug P^1 is inserted in the trunk jack J' , the tip and sleeve conductors are 90 connected to the trunk conductors 412, 413 and lamp 411 is connected to the wire 418, leading to a contact in relay 450 (Fig. 2). The insertion of the plug closes the contact springs 444 and completes the circuit of 95 relay 435 (Fig. 2) so as to start a key-set switch in search of the trunk.

Referring now to Fig. 2, the trunk conductors 412, and 413 from the manual exchange are connected for conversational purposes to the wipers 447 of the first selector switch through the windings of the repeating coil 419 and condenser 421. 100

The wipers 448 act as test wipers and also form a part of the release circuit for the 105 first selector switch D. The relay 445 is actuated when the key-set switch picks out the trunk and in turn closes the circuit of

- relay 440. This latter relay disconnects relay 435 which is the starting relay and is originally energized when the plug P^1 is placed in the jack J^1 . Relay 470 is the 5 rotary repeating relay and responds to impulses from the sending device. 455 is the test relay and remains energized while the first selector switch D is picking out an idle second selector switch. Relay 450 is of a 10 high resistance and is actuated when the called subscriber answers, and the action of this relay removes ground from the wire 418, extinguishing lamp 411 of the cord circuit, (Fig. 1).
- 15 Referring now to Fig. 3, the second selector switch E is operated first in a rotary direction to pick out the row, and then in a vertical direction to pick out an idle contact of the row and is similar to the first selector 20 switch shown at D. Relay 81 is the repeating relay and responds to the impulses from the sending device. Relay 82 is the interrupter relay corresponding to relay 465 (Fig. 2). These respective relays are 25 operated by their vertical magnets and when so operated, open the circuit of the magnet itself, causing the switches to step vertically. Relay 83 is the test relay and remains 30 energized until an idle connector switch is found. Relay 97 is for releasing and becomes 35 energized as soon as the first selector switch places ground on the wire 96. This relay remains energized throughout the conversation and is disconnected when the calling party hangs up his receiver and the operator withdraws the plug P^1 from the jack J^1 . When the relay 97 is released after the 40 switch E has rotated, then the circuit of the release magnet 93 is closed and will restore the switch E to its normal position.
- Referring now to Fig. 4, the connector switch G is provided with wipers 390 which engage contacts leading to the talking conductors of the called line, and also with test 45 wipers 391 leading to the cut-off relay of the called line. 305 and 310 are the repeating relays and respond to impulses from the sending device. 315 is a control relay and prevents battery being connected to the wipers 390 while passing over busy contacts. 320 is the tip relay and responds when the called 50 subscriber removes his receiver. 340 is the ringing relay operated by the commutator 370. 345 is the busy test relay and is operated 55 when a busy line is found and when so operated, connects a suitable busy tone test to the calling subscriber's line. The action of this relay also operates the release magnet 365 restoring the connector switch G.
- 60 Action of relay 345 in addition removes relay 305 and connects ground to the tip conductor 300 through commutator 371. This intermittent ground, actuating relay 450, (Fig. 2) causes lamp 411 (Fig. 1) to flash.
- 65 The controlling or party line switch is

shown at F. The contacts and wipers of the portion J cut on the proper generators to either the tip or sleeve contact of the ringing relay 340 as the case may be. The contacts and wipers of the portion I serve to restore the distributing switch to its normal or idle position. The contacts and wipers of the portion H serve to connect ground to either the tip or sleeve contacts of the ringing relay 340. When the portion J cuts on generator to the tip contact, the portion H cuts on ground to the sleeve contact, and when the portion J cuts on generator to the sleeve contact, the portion H cuts on ground to the tip contact. This arrangement makes 70 it possible to ring subscribers' bells which are connected from either the tip or sleeve side of the line to ground. When the switch F is in its normal position, the wiper of H rests on the contact 334, the wiper of I on 75 the contact 336, while the wiper of J rests upon the contact 338.

The contact 336 of this portion I is connected to the interrupter 385 through the normally open cam springs controlled by the 80 switch G. This arrangement will prevent the switch F from coming to rest so long as the switch G is in an off-normal position, as under these circumstances the wiper I would have no idle resting position. When the 85 switch G is restored, the interrupter 385 is disconnected from the contact 336 and when the wiper reaches the contact under these 90 circumstances, the switch F will be brought to rest. So long as the switch G is off-normal, 95 then the switch F will continue to rotate and serve as a signal to the attendant that a connector switch is tied up.

Figs. 6 and 7 show the method of controlling the trunks leading from the manual 100 exchange.

In Fig. 6 the switch C starts to rotate and pick out the trunk shown in Fig. 2 when the operator inserts the plug in the jack. 254 is the stepping magnet, which when acting causes the switch C to rotate. The relays 251 and 130 become energized when the wiper 255 of the switch C picks out the calling trunk. When these relays are energized, the stepping magnet is disconnected and the 110 controlling circuits extended to the switch Y (Fig. 7). The switch Y picks out an idle key-set switch such as shown in Fig. 8. As soon as the switch C (Fig. 6) finds the trunk, the starting relay 130 (Fig. 7) closes the circuit, causing the stepping magnet 133 to operate. The action of relay 130 also connects the test relay 131 to the test wire 140 through the wiper 280 of the switch Y.

It will be noted that two segments 256 and 125 257 are provided in the switch C which the wiper 255 engages. One of these segments connects relays 251 and 130 in series while picking out a certain group of trunks, while the other segment connects a second test re- 130

lay 252 in series with relay 130 in picking out another group of trunks. In fact the switch C is provided with two test relays, namely, 251 and 252 each one becoming active when 5 picking out a certain group of trunks, such as shown in Fig. 2.

In Fig. 7, the wiper 280 engages the two segments 281 and 282. While the wiper is in engagement with one segment, the test 10 relay 131 for the key-set switches is used when picking out a certain group of key-set switches. This test relay 131 is connected to either one of the two segments 281 or 282, depending upon the action of relay 253 15 (Fig. 6). This relay 253 is energized by the action of relay 252 in picking out a certain group of trunks, and thereby connects the test relay 131 to segment 282. When the test relay 251 is energized in 20 serving a particular group of calling trunks, the relay 253 is not actuated and therefore the test relay 131 is connected to the segment 281.

Referring to Fig. 7, relay 132 becomes 25 energized when the test relay 131 is actuated and connects ground to the winding of this test relay, thereby shunting it. Direct ground is thus placed on the wire 140 through the wiper 280 preventing any other 30 Y switch picking out the same key-set switch. The action of relay 132 also connects ground to the lower portion of switch Y to wire 141 leading to the row contact of a key-set switch. These row contacts 35 of the various key-set switches are not multiplied.

When a key-set switch is picked out by a Y switch, ground is connected to the row contact of the selected switch but at no 40 other.

This allows calls to come in from different groups of trunks at the same time without interference as only one row contact in any key-set switch is grounded at the same time.

45 Other features in connection with Figs. 6 and 7 will be made clear in the detail description of operation. The switch C (Fig. 6) serves to pick out the individual trunk in the group calling while the switch Y (Fig. 50 7) starts to pick out an idle key-set switch as soon as the first selection is completed. The key-set switch starts to pick out the calling trunk, and after doing so, then both the switches C and Y are at once relieved. 55 This method of selection brings the calls in from the different trunks without preference or the selection of the trunk to be first served depends upon the position of the arms of the switch C.

60 Referring now to Figs. 8 and 9, the key-set switch and operator's key-board and sending device are shown. The key-set switch M carries the wipers 167, 168 and 169. The wiper 168 is the row wiper and when 65 the switch rotates, this wiper passes over a

set of contacts until a busy one is found, whereupon the rotary action of the switch is discontinued and the switch starts to step in a vertical direction. While stepping vertically, the wipers 167 and 169 pass over vertical rows or sets of contacts. At the first vertical step of the switch M, the row wiper 70 168 leaves the row contacts.

The wipers 167 serve to connect the tip and sleeve sides of the trunk shown in Fig. 75 2, over which the operator converses with the calling subscriber, and over which the impulses are transmitted. Relay 153 is connected to the row wiper 168 and is operated when the proper row contact is reached. The 80 operation of this relay disconnects the rotary magnet 165 and in its place connects the vertical magnet 164. Relay 154 is connected to the individual test wiper and is actuated when the proper individual test contact in 85 the row or group is found and disconnects the vertical magnet causing the switch M to rest on contacts leading to the calling trunk. 156 is the signal relay and it pulls up in series with relay 445, (Fig. 2), when 90 the trunk is picked out. The operation of the signal relay closes the circuits of the two lamps 243 and 244 (Fig. 9), notifying the operator of a call. 152 is the starting relay and is actuated when the switch Y picks out 95 the idle switch M. 155 responds when the operator presses the button 248 and connects her telephone set across the tip and sleeve conductors of the trunk. 157 is operated when the button 247 is pressed and connects 100 the starting wire controlled by the cam 231 to the stepping magnet 161, thereby causing the shifting switch arms to step over the banks N, O and P. This magnet is operated once at each rotation of the sending device 105 and cuts on the impulses from the key-board in proper sequence. The order of these impulses is as follows: At the first rotation of the sending device, impulses corresponding to the thousands are sent over the tip 110 side of the trunk. At the second rotation a single test impulse is sent over the sleeve side of the trunk. At the third rotation impulses corresponding to the hundreds are sent over the tip side of the trunk and at 115 the fourth rotation a single test impulse is sent over the sleeve side of the trunk. At the fifth rotation selective ringing impulses are sent over the tip side of the trunk, and at the sixth the tens impulses are sent over 120 the sleeve side of the trunk. At the seventh rotation the units impulses are sent over the tip side of the trunk and at the eighth rotation a single test impulse is sent over the sleeve side of the trunk.

125 At the next rotation of the sending device the wiper of the portion P completes the circuit of relay 158 causing the shifting switch to rapidly rotate until it reaches its normal position. Just before reaching this 130

position the circuit of the release magnet 166 of the key-set switch M is energized thereby restoring it to its normal position. Relay 163 is the interrupter relay operated 5 by the magnets 164, 165 and 161.

The operator's key-board shown in Fig. 9 consists of five rows of buttons, each row having ten buttons. Number 1 button of each row is connected to a contact operated 10 by the cam 232. Number 2 button of each row is connected to a contact operated by the cam 233. Corresponding buttons in each row are connected to similar contacts. The contact controlled by the cam 232 is closed 15 just long enough to keep the relay 160 (Fig. 8) energized, while one impulse is being transmitted by the commutator 242. If number 10 button is pressed, relay 160 would be closed by the cam 241 just long enough 20 for ten impulses to be transmitted by the commutator 242. The contacts of the commutator 242 are connected directly to the normally open contact of relay 160, and when this relay is energized the impulses 25 are connected to either the tip or sleeve sides of the trunk depending upon the position of the arm in regard to the N portion and of the switch.

The buttons or keys shown in these five 30 rows, (Fig. 9) are of the usual locking and indicating type. When any one button of a certain row is depressed, it will release the button formerly depressed. The buttons 246, 247 and 248 are of the non-locking type 35 and the contacts controlled by them are only closed while the operator is pressing the button.

Other points in the various circuits will 40 be brought out in the detailed description of operation which is as follows: Referring now to Fig. 1, when a subscriber at the manual switch-board desires to converse with some one in the semi-automatic exchange, the operator places the answering plug P^2 into the 45 calling jack associated with his line. I have not illustrated the calling subscriber's line circuit as it can be of any desired type. It is only necessary that when the plug P^2 is inserted in the jack of the calling line that the associated signal be disconnected. In this case the calling in signal is disconnected and the ring-off drop 460 which is 50 connected to the tip and sleeve conductors of the cord, responds when the calling party wishes to become disconnected.

The operator places the calling plug P^1 into an idle trunk jack J^1 , thereby closing the contact springs 444. The closing of these 60 springs completes the circuit of the lamp 414, or other multiple lamps, thus notifying the operators at the other positions that this particular trunk is busy. The closing of the contacts 444 connects ground to relay 65 435 as follows: ground, 444, 434, cam springs

441, 432, contacts of relay 440, 433, 435 to battery B. The energizing of relay 435 completes the circuit of the stepping magnet 254, Fig. 6, as follows: battery B, contacts of relay 435, 79, contacts of relay 252, contacts of relay 251, 254, contacts of relay 250 to ground. The magnet 254 operating closes the circuit of relay 250, thereby opening its own circuit. The interruptions set up between the relay 250 and the magnet 254 75 causes the arms of the switch C to rotate. As soon as the calling trunk, (Fig. 2) is found, the test relay 251, (Fig. 6) and the starting relay 130, (Fig. 7) are closed as follows: battery B, contacts of relay 435, 80 62, wiper 255, segment 256, 251, 262, 679, 130 to ground. The operation of relay 251 disconnects the stepping magnet 254, thereby bringing the switch wipers of C to rest on contacts associated with the trunk, (Fig. 2). Battery is now connected to the individual test contact of the key-set switch, (Fig. 8) as follows: battery B, contacts of relay 435, 85 62, wiper 258, 620 to the individual contact of the switch M, (Fig. 8).

The energizing of relay 130 connects battery B to the stepping magnet 133 through the contacts of relays 132 and 131. The circuit of the stepping magnet 133 is interrupted by the action of the relay 134, thereby causing the switch Y to rotate and pick out an idle key-set switch such as shown in Fig. 8. As soon as a key-set is found, the circuit of relay 131 is closed as follows: ground, contacts of relay 130, 137, 131, 259, contacts of relay 253, 260, segment 281, wiper 280, 140, 152, 195, cam springs 196 to battery B through the operator's jack 400. The energizing of relay 131 disconnects the stepping magnet 133 and closes the circuit of relay 132. The action of relay 132 places ground to wire 140 by the path previously traced. This ground shunts out relay 131 and prevents other Y switches from coming 95 to rest on contacts leading to this wire 140 which is multiplied to contacts of other Y switches. Relay 132 disconnects the stepping magnet 133 after relay 131 falls back and prevents any further action of the 100 switch Y. The action of relay 132 also connects ground to the row contact over wire 141.

The closing of the circuit of relay 152, 110 (Fig. 8) connects ground to the rotary magnet 165 through the contacts of relays 163 and 153, thereby causing the switch M to rotate. As soon as the grounded row contact is engaged by the wiper 168, the circuit of relay 153 is closed. The action of relay 153 115 disconnects the rotary magnet and in its place connects the vertical magnet 164, thereby causing the switch M to step vertically until the individual test contact is found. The individual test contact is ren- 120 125 130

dered busy by the action of the switch C, (Fig. 6) placing battery on wire 620 leading to this individual test contact. As soon as this contact is found, the circuit of relay 154 is closed. This relay disconnects relay 152 and prevents any further action of the switch M. Relay 152 in turn disconnects relay 153, thereby placing relays 156 and relay 445, (Fig. 2) in series as follows: ground, contacts of relay 153, 175, contacts of relay 157, contacts of relay 155, 180, 156, 193, contacts of relay 158, wiper 169, 59, 445 to battery B. The operation of relay 445 closes the circuit of relay 440 and this latter relay 15 acting disconnects relay 435. Relay 435 being disconnected in this manner, opens the circuits of relays 251 and relay 130 respectively in Figs. 6 and 7. As soon as relay 251 falls back, the circuit of the stepping 20 magnet 254 is again in condition to be actuated by calls from other trunks. Relay 130, (Fig. 7) falling back unlocks relay 132, which in turn places the stepping magnet 133 in condition to be operated by other 25 calls.

It will be noted from the foregoing description of operation that the switch Y is the main switch for picking out idle key-set switches, while switch C is an intermediate 30 switch enabling quick coöperation between the trunks and key-sets. As soon as the key-set switch picks out the trunks, the main switch Y and the intermediate switch C are at once relieved and are ready to control 35 other calls.

The wire 79 shown in Fig. 6 is common to a group of primary trunks. There may be ten of these trunks in this particular group. A call from any trunk in this group 40 will bring the test relay 251 into action. A wire 779 leads to another group of trunks. There may be ten trunks in this group and a call from any one of these trunks will place the test relay 252 in condition to be operated at the proper time. The relay 253 is used in conjunction with the test relay 252 and serves to shift the test relay 131 (Fig. 7) to a particular group of key-set switches. The wiper 280 and segment 281 with which 45 it coöperates serves to pick out a certain group of key-set switches. There may be ten of these switches to a group and a similar group connected by means of the segment 282.

55 Relay 156 becoming energized closes the circuits of the two lamps 243 and 244, (Fig. 9) notifying the operator of a call. The operator upon receiving this signal, presses the button 248 operating relay 155, thereby connecting her telephone set across the tip and sleeve conductors of the trunk. The action 60 of relay 155 disconnects the signal relay 156, thereby extinguishes lamps 243 and 244, but at the same time lighting the lamp 245. Relay 156 becoming disconnected allows relay

445 (Fig. 2) to fall back and close the tip and sleeve conductors of the trunk so as to allow the operator to converse with the calling subscriber.

Each operator is provided preferably 70 with three key-sets such as shown in Fig. 9, enabling her to handle calls without loss of time. While a call is going through on one key-set she can receive calls on the other two.

The cams of the sending device shown at 75 230 to 241 inclusive may be common to a group of key-sets. The commutator 242 is preferably individual to one key-set or to one operator.

In Fig. 8, the plug connected to the receiver of the operator's telephone set is shown as withdrawn from the jack 400, however it is to be understood that when the operator is on duty the plug is inserted and the jack springs are closed.

In the present instance I have shown the exchange to be of 10,000 lines capacity and in case of larger exchanges it would be necessary to add additional rows of buttons to the operator's key-board and insert additional 90 selector switches.

The operator after getting the proper number from the subscriber presses one button in each row so as to set up the number corresponding to that desired, and then 95 presses the starting button 247. The pressing of this button closes the circuit of relay 157 as follows: ground, 247, 186, 157, 193 contacts of relay 158, 170, 169, 59, 445 to battery B. The relay 445 again operating 100 opens the trunk conductors to prevent the calling subscriber hearing the impulses.

The operating of relay 157 disconnects relay 155, extinguishes lamp 245 and causes the lamp 244 to light. The action of this 105 relay also connects the starting wire 189 to the contact operated by the cam 231 to the stepping magnet 161. As soon as the cam contact springs are closed, the wipers of the shifting switch at N, O, P take one step and 110 connect the impulse wire 191 to the tip side of the trunk 150 through the contacts of relay 160.

If number 9 button in the row R is pressed, the relay 160 will be held energized 115 by the operation of the cam 240 until nine impulses have been transmitted by the commutator 242. These impulses operate the rotary relay 470, (Fig. 2) as follows: ground, 242, 191, 190, 192, contacts of relay 160, N, 150, 167, 60, 422, cam springs 442, 470 to battery B. The relay 470 responding to these impulses closes the circuit of the rotary magnet 475, causing the first selector switch D to rotate and bring the wipers opposite a group of trunks in the ninth row.

120 After these rotary impulses have been sent, the starting cam 231 causes the shifting switch to take another step, thereby connecting wire 198 to the sleeve side of the trunk 130

151. The relay 160 is held energized by the action of the cam 230 until a single impulse is transmitted. This impulse closes the circuit of relay 455, (Fig. 2) as follows: ground, 5 242, 191, 190, 192, contacts of relay 160, 198, N, 151, 167, 61, cam springs 442, 438, 455 to battery B. The operating of relay 455 closes the circuit of the vertical magnet 480 as follows: Battery B, contacts of relay 465, contacts of relay 455, 480 to ground. The magnet 480 acting closes the circuit of relay 465, which in turn opens the circuit of the magnet itself. The action set up between the relay and the magnet causes the latter to vibrate 10 and to step the switch D vertically. When the circuit of relay 465 is closed by the action of the magnet 480, the circuit of relay 455 is itself partially opened, but it will remain energized so long as the test wiper 15 20 448 is passing over grounded or busy contacts. While the relay 465 is operated and the wiper 448 comes to an idle contact, the relay 455 will at once become deenergized and disconnect the vertical magnet 480. The 25 controlling of the test relay 455 in this manner insures a full step of the magnet 480 as the wiper 448 fully engages the test contacts before the circuit of the relay 455 is opened by the action of the relay 465. 30 35 As soon as the switch D takes its first vertical step, or while in the act of taking this step, the cam springs 442 are opened, thereby disconnecting relays 455 and 470 respectively from the tip and sleeve sides of the trunk.
- At the third rotation of the sending device impulses corresponding to the hundreds are sent over the tip side of the trunk to the second selector, (Fig. 3) thereby operating 40 relay 81. This relay is connected to the tip side of the trunk 90 through the cam springs 88. The action of relay 81 closes the circuit of the rotary magnet 85 causing the switch E to rotate and bring its wipers opposite a 45 row of contacts leading to connector switches.
- At the fourth rotation of the sending device a single test impulse is sent over the sleeve side of the trunk operating relay 83. The action of this relay closes the circuit of 50 the vertical magnet 84, causing the switch E to step vertically until an idle connector switch is found. The test relay 83 is controlled in the same manner as the test relay 455, (Fig. 2). At the first vertical step of 55 the switch E the cam springs 88 are opened thereby disconnecting relays 81 and 83 respectively from the tip and sleeve sides of the trunk.
- The calling subscriber is now connected to 60 contacts of an idle connector switch. At the fifth rotation of the sending device impulses corresponding to the button pressed in the row V, (Fig. 9) are sent over the tip side of the trunk operating relay 310 of the connector, (Fig. 4). The action of this relay

closes the circuit of the stepping magnet 360 of the party line distributing switch F as follows: ground, 321, contacts of relay 330, 323, 360, 318, contacts of relay 320 to battery B. The switch F takes a number of 70 steps corresponding to the impulses transmitted from the sending device.

In the present instance I have shown the generator 356 connected to the first two contacts in the bank J so that if either one or 75 two impulses are transmitted, this same generator will remain connected to the tip side of the trunk 304. If six or seven impulses are transmitted, this same generator will be connected to the tip side of the trunk 302. 80

The action of relay 310 also closes the circuit of relay 315 as follows: battery B, 319, 315, contacts of relay 305, 306, 102, (Fig. 3), 89, contacts of relay 82 to ground.

At the sixth rotation of the sending device 85 impulses corresponding to the button pressed in the row T are sent over the sleeve side of the trunk operating relay 305. The operation of this relay unlocks relay 315 and closes the circuit of the rotary magnet 355 90 as follows: battery B, contacts of relay 305, 314, cam springs 380, 316, 355 to ground. The rotary magnet operating causes the connector switch G to rotate and come opposite a group of contacts in which the desired line 95 is connected. The action of relay 305 also closes the circuit of relay 330, which disconnects the stepping magnet 360 of the switch F and in its place connects the vertical magnet 350. 100

At the seventh rotation of the sending device vertical impulses are sent over the tip side of the trunk operating relay 310 the second time. This relay closes the circuit of the vertical magnet 350 causing the switch 105 G to step vertically and bring the wipers into engagement with contacts leading to the desired line. The action of relay 310 again energizes relay 315, preventing annoying clicks to parties talking while the wipers are 110 passing over contacts of busy lines. When the switch G takes a vertical step, the cam spring 380 operates and disconnects the rotary magnet 355.

At the eighth rotation of the sending device a single test impulse is sent over the sleeve side of the trunk operating relay 305 a second time. This relay operating connects the test relay 345 directly to the test wiper 391. If the called line is busy, this 120 relay 345 will become energized, lock itself to ground to the test wire 306. The action of this relay places ground on the release magnet 365 and causes the switch G to restore and also connects a suitable busy tone 125 test to the calling subscriber, notifying him that the line is busy. The action of this test relay 345 also connects ground through a suitable commutator or interrupting device. The ground being placed on the trunk 130

wire 300 causes relay 450, (Fig. 2) to operate intermittently. This relay operating in this manner causes the lamp 411, (Fig. 1) to flash, thus notifying the operator that the 5 called line is busy.

In case the called line is not busy, the relay 345 will not be affected. Relay 305 acting the second time unlocks relay 315 and in falling back places the relay 325 in series 10 with the cut-off relay 1, (Fig. 5) by the following path: battery B, 313 contacts of relay 315, 312, 325, 311 back contact of relay 305, 308, 391, 107, 1 to ground. The action of relay 108 disconnects the line relay of 15 the called line. The action of relay 325 closes the sleeve side of the trunk and disconnects the repeating relay 310. The action of this relay also places battery to the winding of the tip relay 320 and 20 closes the circuit of the ringing relay 340 as follows: ground, commutator 370, 340, 326, contacts of relay 325, 324, contacts of relays 330 and 315, 322, vertical magnet 350 to battery B. The action of 25 this ringing relay connects the generator to the called line, thus ringing the subscriber's bell A—A at intervals.

At the next rotation of the sending device the relay 158, (Fig. 8) is connected to battery through the bank P. The action of this relay places ground to the magnet 161 and also unlocks relay 157. The magnet 161 vibrates rapidly and causes the shifting switch to rotate until the wipers reach their 35 normal resting position. Just before reaching this position, however, the wiper of the portion P places the relay 158 in series with the release magnet 166. The action of this magnet causes the switch M to restore and 40 disconnect the operator's key-set from the trunk.

When the called subscriber removes his receiver during the silent interval he energizes relay 320. The action of this relay 45 unlocks relay 330 and disconnects relay 305 and closes the tip side of the trunk. The falling back of relay 330 disconnects the ringing relay 340. The calling and called subscriber are now able to converse without 50 interference over the talking circuit indicated throughout the various figures by the heavy lines.

When the called subscriber hangs up his receiver the relay 320 falls back and the 55 circuit of the magnet 360 is closed as follows: ground, commutator 353, I, 398, contacts of relay 330, contacts of relay 315, 321, the contacts of relay 330, 323, 330, 318 to battery B, through the contacts of relay 320. The magnet 360 will continue to vibrate until 60 the wiper of the portion I rests on the contact 336 providing the switch G is restored, removing interrupted current from this resting contact. Just before the wiper 65 at I reaches the resting contact, the wiper

at H closes the circuit of the release magnet 365 as follows: battery B, 365, 332, H, 327 to ground, through the contacts of relay 315. The action of magnet 365 restores the switch G to its normal position.

The calling subscriber ringing-off throws the ring-off drop 460, (Fig. 1) notifying the operator that he is through talking.

When the called subscriber hung up his receiver, the relay 450 fell back, thus closing the circuit of the lamp 411, (Fig. 1) notifying the operator of the fact. When the called subscriber answers his telephone, and while his receiver is off the hook, the relay 450 remains energized in multiple with the 75 tip relay 320. This relay remaining energized throughout the conversation, keeps the lamp 411, (Fig. 1) extinguished.

The operator getting these disconnect signals, withdraws the plug P¹ from the jack J¹, thereby removing ground from relay 440. This relay in falling back closes the circuit of the release magnet 485 as follows: Battery B, contacts of relay 445, 427, contacts of relay 440, 485, 436, wipers 448 which are short circuited by the bank contacts 429, to ground, through contacts of relay 465. The circuit of magnet 485 will remain closed until the wipers 448 leave the contacts. As soon as these wipers leave the contacts, the 95 circuit of the magnet is opened and all parts of the switch D are restored to their normal position. The restoring of switch D removes ground from relay 98, (Fig. 3). This relay in falling back closes the circuit of the 100 release magnet 93, thereby restoring the switch E to its normal position. The circuit of the magnet 93 is kept closed until the switch E opens the cam springs 87.

In case the called party does not answer, 105 the operator also releases the connector switch. This release is brought about as follows: When the second selector switch, (Fig. 3) restores, ground is removed from the test wire 306, thereby unlocking the control relay 330 just as though the called subscriber had answered and energized the tip relay 320. The relay 330 falling back in this manner closes the circuit of the stepping magnet 360 by the same path as formerly traced, thereby restoring all parts of 110 the connector switch to its normal position.

Having described my invention what I claim and desire to secure by Letters Patent is,

1. In a telephone exchange system, the combination of an operator's position, a signal at said position, wanted subscribers' lines, means for establishing a connection 125 from said position to a wanted line comprising a selector and a connector switch, a single test relay associated with said connector switch, means for operating said relay in case the wanted line is busy, intermit- 130

- tent means associated with said connector switch, said intermittent means being connected immediately through the contacts of said relay to cause the intermittent operation of said signal.
2. In a telephone exchange system, a calling and a called subscriber's line, an operator's position, a signal at said position, automatic switching mechanism including 10 selector and connector switches for extending the connection from the calling to the called line, a test relay associated with said connector switch, means for connecting said test relay directly to the line terminals of 15 the wanted line, means for operating said relay in case the called line is busy, and means connected directly through the contacts of said relay to cause the intermittent operation of said signal.
- 20 3. In a telephone exchange system, the combination of a manual exchange switchboard provided with jacks, calling subscribers' lines terminating in certain of the jacks, an operator's cord circuit having an answering 25 plug and a calling plug connected thereto, a visual signal associated with said cord circuit, automatic switching mechanism including first selector, second selector and connector switches, links interconnecting 30 said switches, trunk lines terminating in other jacks on the manual switchboard and in the first selector switch, wanted subscribers' lines terminating in the connector switch, and means associated with the connector switch and arranged to operate said 35 signal in the cord circuit to notify the operator at the manual exchange that the called or wanted line is busy.
4. In a telephone exchange system, the 40 combination of a manual exchange switchboard provided with jacks, calling subscribers' lines terminating in certain of the jacks, an operator's cord circuit having an answering plug and a calling plug, a visual signal 45 associated with the calling plug of the cord circuit, automatic switching mechanism comprising first selector, second selector, and connector switches, interconnecting link circuits, trunk lines terminating in certain 50 jacks on the manual exchange switchboard and in the first selector switch, wanted subscribers' lines terminating in the connector switches, and means for intermittently operating the signal in the cord circuit, said 55 means being actuated when the connector switch connects the link circuit of the calling subscriber with a busy called or wanted subscriber's line.
- 60 5. In a telephone exchange system, the combination of a manual exchange switchboard provided with jacks, calling subscribers' lines terminating in certain of the jacks, an operator's cord circuit having an answering plug and a calling plug, an operator's 65 telephone set arranged to be connected with the conductors of the cord circuit, a signal also connected with the conductors of the cord circuit and responding when the calling subscriber wishes to become disconnected, a supervisory lamp connected to the calling 70 plug of the operator's cord circuit, automatic switching mechanism comprising first selector, second selector and connector switches, link circuits interconnecting said switches, trunk lines terminating in certain 75 jacks on said manual switchboard and in the first selector switch, wanted subscribers' lines terminating in said connector switches, means whereby said lamp is energized when the calling plug of a cord circuit is inserted 80 in a jack connected to a trunk line, and means associated with the connector switch for intermittently flashing said lamp so as to notify the manual operator that the 85 called or wanted line is busy.
6. In a telephone exchange system, the combination of a manual exchange switchboard provided with jacks, calling subscribers' lines terminating in certain of the jacks, an operator's cord circuit having an answering 90 plug and a calling plug, a supervisory signal connected with the cord circuit, automatic switching mechanism including first selector, second selector and connector switches, link circuits interconnecting 95 the switches, trunk lines terminating in certain other jacks on the manual switchboard and in the switching mechanism, wanted subscribers' lines terminating in the connector switches, means whereby said supervisory 100 signal is energized when the calling plug is inserted in a jack connected to a trunk line terminating in the switching mechanism, means for deenergizing the signal when a wanted subscriber responds, and means for 105 intermittently disabling the signal and for connecting a busy tone test to the calling subscriber's line to simultaneously notify the manual operator and the calling subscriber that the wanted or called line is 110 busy.
7. In a telephone exchange system, the combination of a manual exchange switchboard provided with jacks, calling subscribers' lines terminating in certain of the 115 jacks, a manual operator's cord circuit having an answering plug and a calling plug, means for notifying the manual operator when the calling subscriber desires to be disconnected, a supervisory lamp in the operator's cord circuit, automatic switching mechanism at a semi-automatic exchange and comprising first selector, second selector and connector switches, link circuits interconnecting said switches, trunk lines terminating in certain jacks on the manual 120 switchboard and in first selector switches at the semi-automatic exchange, wanted subscribers' lines terminating in the connector switches, means whereby the supervisory 125 130

- lamp is energized when the calling plug is inserted into a jack connected to a trunk line terminating in a first selector switch, electrically operated means actuated when
- 5 the wanted subscriber responds for deenergizing the supervisory lamp, and means for intermittently flashing the supervisory lamp, connecting a busy signal to the calling subscribers' circuit and restoring the connector switch comprising a relay operated when the contactors of the connector switch engage the contacts of a busy called line, a grounded commutator connected in circuit with said electrically operated means by said 10 relay, and a release magnet energized by the operation of said relay.
8. In a telephone exchange system, a calling subscriber's line, trunk lines, means for connecting the calling subscriber's line to an idle one of said trunk lines, operators' key sets, automatic key set switches associated with said key sets, an auxiliary automatic switch for picking out an idle key set switch, an intermediate automatic switch associated 15 with said auxiliary switch for designating the trunk to be selected by the idle key set switch.
9. In a telephone exchange system, a calling subscriber's line, a wanted or called subscriber's line, automatic switching mechanism in which the wanted or called subscriber's line terminates, trunk lines adapted to be connected with the calling subscriber's line, operator's key sets, automatic key set switches associated with said key sets, an auxiliary automatic switch for picking out an idle key set switch, an intermediate automatic switch associated with said auxiliary switch for designating the trunk to be selected by the idle key set switch.
10. In a telephone exchange system, the combination of a manual exchange switchboard provided with jacks, calling subscribers' lines terminating in certain of the jacks, semi-automatic operator's key sets, automatic key set switches associated with said key sets, an auxiliary automatic switch for picking out an idle key set switch, an intermediate automatic switch associated 15 with the auxiliary switch and groups of trunk lines terminating in certain other jacks on the manual switchboard and at contacts on said intermediate switch, the intermediate switch being arranged to pick out calling trunk lines.
11. In a telephone exchange system, the combination of a manual exchange switchboard provided with jacks, calling subscribers' lines terminating in certain of the jacks, an operator's cord circuit having an answering plug and a calling plug, a semi-automatic operator's key set, automatic key set switches associated with said key set, an auxiliary automatic switch adapted when actuated to pick out an idle key set switch,
- an intermediate automatic switch associated with the auxiliary switch, groups of trunk lines terminating in jacks at the manual switchboard, a conductor associated with said group of trunks and connected to the starting mechanism for said intermediate switch to operate the latter when the calling plug of the cord circuit is inserted into a jack associated with any one of said trunks, and means whereby the intermediate switch is adapted to serve a plurality of groups of trunks.
12. In a telephone exchange system, the combination of a manual switchboard provided with jacks, calling subscribers' lines terminating in certain of the jacks, a manual operator's cord circuit having an answering plug and a calling plug, a semi-automatic operator's keyboard provided with key sets, automatic key set switches associated with said key sets, auxiliary automatic switches adapted to select an idle key set switch, groups of primary trunk lines terminating in certain jacks on the manual switchboard, an intermediate automatic switch in which the groups of trunk lines terminate and which is adapted to select the calling trunk, means for actuating said switch when said calling plug is inserted in a jack associated with a trunk of one of said groups, a plurality of elements on the intermediate switch associated with separate groups of trunks, and adapted to determine the auxiliary switch to be utilized, and means for displacing the elements not connected in circuit so that other connections to the intermediate switch may not be made.
13. In a telephone exchange system, the combination of a manual switch board provided with jacks, subscribers' calling lines terminating in certain other jacks, a manual operator's cord circuit provided with answering and calling plugs, a semi-automatic operator's keyboard having key sets, automatic key set switches associated with the key sets, auxiliary automatic switches adapted when actuated to select an idle key set switch and comprising two banks of contacts, one of said banks being associated with the multiple contacts of said key set switches, the other bank being connected with the row contact of the key set switches, wipers operating over the contacts of said auxiliary switch, groups of trunk lines terminating in other jacks in the manual switchboard, an intermediate switch in which said groups of trunk lines terminate and adapted to select a calling trunk, means whereby the auxiliary switch operating is disabled when a trunk of a certain group is selected by the intermediate switch until the auxiliary switch finds an idle selector switch, means for releasing the auxiliary switch until an idle selected switch is found and permitting the intermediate switch to pro-

ceed to select another calling trunk in the same revolution of the intermediate switch.

14. In a telephone exchange system, the combination of groups of calling trunks adapted to be connected to calling subscribers' lines, an intermediate automatic switch for selecting the calling trunks, means controlled by the calling trunk for actuating said intermediate switch, a semi-automatic operator's keyboard provided with key sets, automatic key set switches associated therewith, auxiliary automatic switches each adapted to select an idle key set switch having contacts connected in multiple to row conductors on the key set switches, other contacts on said auxiliary switch connected to separate row contacts on the key set switches, a plurality of test relays associated with the intermediate switch and arranged to be actuated when connection is made with an individual starting relay of a trunk by the wiper of the intermediate switch of one of said groups, and means for disabling the auxiliary switch while it is in connection with a key set switch selected thereby.

15. In a telephone exchange system, the combination of a manual exchange switchboard provided with jacks, calling subscribers' lines terminating in certain of the jacks, an operator's cord circuit provided with an answering plug and a calling plug, a semi-automatic keyboard having key sets, automatic key set switches associated therewith, an operator's telephone set adapted to be connected to any one of the key set switches, automatic switching mechanism comprising an intermediate switch and an auxiliary switch, trunk lines terminating in jacks in the manual exchange in the intermediate automatic switch, means for operating the intermediate switch when a plug is inserted into a jack connected to a calling trunk set, operating means being arranged inoperative when the intermediate switch selects the trunk calling, means for connecting battery to individual test contacts on the key set switches, means arranged active when the calling trunk is located by the intermediate switch for operating the auxiliary switch, means arranged active when the auxiliary switch locates an idle key set switch for disabling the auxiliary switch, and means for operating the key set switch, said key set switch operating means being arranged inactive when a contact thereon becomes connected to the individual test contact which has battery connected thereto.

16. In a telephone exchange system, the combination of a manual exchange switchboard provided with jacks, calling subscribers' lines terminating in certain of the jacks, an operator's cord circuit having an answering plug and a calling plug, a disconnected signal and an operator's tele-

phone set associated therewith, semi-automatic keyboard having key sets and an operator's telephone set associated therewith, key set switches for connecting subscribers' lines to the keyboard, automatic switching mechanism for picking out idle key set switches comprising an intermediate switch and an auxiliary switch, trunk lines terminating in certain other jacks on the manual switchboard and in the automatic switching mechanism, means for operating the intermediate switch when said calling plug is inserted in a jack associated with one of a group of trunks, means for rendering said operating means inoperative when the intermediate switch selects the calling trunk in the group calling comprising a test relay controlling the circuit of the operating means, a starting relay associated with said test relay, means for actuating the auxiliary switch rendered operative when said starting relay is energized and rendered inoperative when the auxiliary switch selects an idle key set switch, means for operating the key set switch selected, and means for relieving the intermediate and auxiliary switch when the key set switch becomes connected to the trunk calling.

17. In a telephone exchange system, the combination of a manual switchboard provided with jacks, subscribers' calling lines terminating in certain of the jacks, an operator's cord circuit having an answering plug and a calling plug, a semi-automatic keyboard having key sets, an impulse sending device associated with the key sets, means for successively connecting the impulse device to the tip and sleeve conductors of a subscriber's line, automatic key set switches associated with the keyboard for connecting calling subscribers' lines to the key sets, automatic switching mechanism including an intermediate switch and auxiliary switches, groups of trunk lines terminating in certain other jacks at the manual switch board in the automatic switching mechanism, means common to groups of said trunks for operating the intermediate switch, means for disabling the switch operating mechanism and dissociating all other groups of trunks when the intermediate switch selects a calling trunk of one of said groups, means for operating the auxiliary switch rendered active when the intermediate switch selects said calling trunk and rendered inactive when the auxiliary switch selects an idle key set switch, means for operating said key set switch, and means for relieving the intermediate switch and auxiliary switch when the key set switch becomes associated with the calling trunk.

18. In a telephone exchange system, the combination of a manual switchboard having jacks, calling subscribers' lines terminating in certain of the jacks, an operator's tele-

- cord circuit having an answering plug and a calling plug, a semi-automatic keyboard having key sets, key set switches for temporarily associating subscribers' lines with the 5 keyboard, automatic switching mechanism including an intermediate switch and auxiliary switches, groups of trunk lines terminating in certain other jacks in the manual switchboard and in said automatic switching 10 mechanism, means common to groups of trunks for operating said intermediate switch, means for dissociating the remaining groups when one of the group of calling trunks is selected and for connecting battery 15 to a contact of the key set switch, means for operating the auxiliary switch, means for disabling the intermediate switch operating means when the calling trunk is selected and simultaneously energizing the auxiliary 20 switch operating means, means for disabling the auxiliary switch operating means when an idle key set switch is selected, means for connecting ground to a contact of the key set switch and for starting the operation of the 25 key set switch when an idle one is selected, means for releasing the intermediate switch and auxiliary switch when the key set switch becomes connected to the trunk calling. 30 19. In a telephone exchange system, the combination of a manual exchange switchboard provided with jacks, calling subscribers' lines terminating in certain of the jacks, groups of trunk lines terminating in certain other jacks, an operator's cord circuit having an answering plug and a calling plug for connecting a calling subscriber with one of said groups of trunks, semi-automatic keyboard having key sets and an operator's 35 circuit associated therewith, key set switches associated with the keyboard for temporarily connecting the semi-automatic operator's telephone set with a calling trunk line, automatic switch mechanism including an 40 intermediate switch and auxiliary switches, said trunk lines also terminating in said automatic switching mechanism, means for rotating said intermediate switch common to two groups of trunks, means for disabling 45 said rotating means when the conductor of the intermediate switch selects the trunk of the group calling and simultaneously dissociating the other group from the switch operating means, means for 50 rotating said intermediate switch common to the group calling and simultaneously dissociating the other group from the operating means of the intermediate switch, means 55 for rotating an auxiliary switch, means for energizing said rotating means when the other group of calling lines is dissociated, means for disabling said rotating means when an idle key set switch is selected, 60 means for preventing the selection of other auxiliary switches of the key set switch selected, means for operating the key set switch selected, and means for disabling the operating means and releasing the intermediate and auxiliary switch when the select- 65 ed key set switch connects the semi-automatic operator's circuit with the trunk calling. 70 20. In a telephone exchange system, the combination of a manual switchboard provided with jacks, calling subscribers' lines terminating in certain of the jacks, groups of trunk lines terminating in other jacks and an operator's cord circuit having an answering plug and a calling plug, a manual 75 operator's telephone set adapted to be connected with said cord circuit, semi-automatic keyboard provided with key sets, a semi-automatic operator's telephone set associated with said keyboard, automatic key set 80 switches adapted to temporarily connect a calling trunk with the keyboard and telephone set associated therewith, automatic switching mechanism including an intermediate switch and auxiliary switches, said 85 trunk lines also terminating in the said switching mechanism, said intermediate switch having two sets of contacts, segments associated with one set of contacts, wipers adapted to move over the contacts, means 90 common to two groups of trunk lines for operating said intermediate switch to move the wipers thereof over the segments and contacts to select the calling trunk connected to the switch and simultaneously connect 95 battery to contacts on the key set switches, means for disabling the intermediate switch operating means when the said intermediate switch selects a trunk of the group calling and simultaneously dissociating the other 100 group from the switch operating means, means for rotating the auxiliary switch said auxiliary switch comprising two sets of contacts, one of said sets of contacts having lines connected in multiple with other auxiliary switches and with the starting mechanism of a key set switch operating means, said last mentioned contacts having two segments associated therewith, wipers moving 105 over the segments and the contacts of the multiplied lines, means for energizing said auxiliary switch operating means to rotate the contactor thereof and connect the multiplied lines to ground through a conductor, the connection of which is dependent upon 110 the group of trunk lines calling, means for disabling the auxiliary switch operating means when an idle key set switch is found, means for operating said key set switch, means comprising another conductor on said 115 auxiliary switch for connecting ground to a row contact of the key set switch selected and no other, means for preventing the interference of any of the other auxiliary switches with the connection of the operative auxiliary switch and the selected key set switch, and means for releasing the intermediate and auxiliary switches when the selected key set switch comes to rest on the contacts leading to the calling trunk. 120 125 130

21. In a telephone exchange system, the combination of a manual exchange switch-board provided with jacks, calling subscribers' lines terminating in certain of the 5 jacks, groups of trunk lines terminating in certain other jacks, an operator's cord circuit having an answering plug and a calling plug, a manual operator's telephone set adapted to be connected to the cord circuit, 10 a semi-automatic keyboard provided with key sets, a semi-automatic operator's telephone set associated with the keyboard, key set switches adapted to temporarily connect calling lines with the semi-automatic operator's telephone set and the key sets, automatic switching mechanism including an intermediate switch and auxiliary switches said groups of trunk lines terminating in the 15 automatic switching mechanism, signals associated with the jacks connected to the trunk lines adapted to be energized when the calling plug is inserted in a jack of a calling line or a calling line multiplied therewith, a starting relay for each group 20 of trunk lines arranged to be energized when the calling plug is inserted in the jack of a wanted trunk, operating mechanism for the intermediate switch common to two groups of trunk lines and connected to the 25 starting relays thereof by contacts 79 and 779 said starting relay being adapted to energize the operating mechanism, the intermediate switch having two independent contactors each of which is adapted to move 30 over sets of contacts said sets of contacts being connected to battery by said starting relay, two segments associated with one of said sets of contacts, relay circuits terminating in said segments whereby one of two 35 relays is operated depending on the position of the contactor of the intermediate switch which moves over the segments, the relay associated with the segment which is operated 40 disabling the intermediate switch operating means and dissociating the other group of trunks the other conductor of the intermediate switch being adapted to connect battery from said starting relay to a contact on the key set switch, operating means for 45 the auxiliary switches, means in series with said relays connected to the segments of the intermediate switch and actuated when the intermediate switch selects the calling trunk for connecting energy to the auxiliary 50 switch operating means said auxiliary switch having banks of contacts and segments associated therewith, rotatable contactors movable over the segments and contacts to interconnect them, conductors connected to 55 relays for starting the key set switches connected in multiple to the auxiliary switches, conductors terminating in the other bank contacts and in the row contacts of individual key set switches, means 60 whereby a test relay and ground are con- 65

nected to the multiple conductors and energizing said last mentioned test relay when the contactors associated with bank of contacts engages the contact of the conductor leading to the starting relay of an idle key set switch, means for connecting grounds to the conductor leading to the individual row contact of the idle key set switch selected, means comprising a relay in series with the multiplied conductors for disabling the auxiliary switch operating means when an idle key set switch is selected, said last mentioned test relay being shunted or disabled when the idle key set switch is selected so as to prevent the interference of another auxiliary switch, with the key set switch selected, means for locking ground to the row contact of the key set switch selected and to the multiplied conductor and starting relay of the key set switch selected, and means for releasing the intermediate switch and the auxiliary switch when the key set switch selects the trunk following.

22. In a telephone exchange system, the combination of calling subscribers' lines, wanted subscribers' lines, automatic switching mechanism for interconnecting the lines including first selector, second selector and connector switches, a relay associated with the second selector switch, means for releasing a first selector switch rendered inactive when said first selector switch is actuated, means for releasing the second selector switch associated with said first selector switch and rendered inoperative when said relay is energized and rendered operative, an operator's position, and means at the operator's position for actuating the release magnet associated with the first selector switch whereupon the relay controlling the release magnet associated with the second selector switch is deenergized and the second selector release magnet is actuated.

23. In a telephone exchange system, the combination of subscribers' lines, switching mechanism for selecting the lines including an automatic switch, means for operating said switch, means for restoring said switch to an inoperative position, said restoring means serving as a signal when said automatic switch fails to restore.

24. In a telephone exchange system, the combination of subscribers' lines, switching mechanism for interconnecting the lines including an automatic switch, means for restoring said switch, means associated with said automatic switch for energizing said restoring means and rendered operative when the automatic switch has interconnected lines, said last named means serving as a signal to an attendant when the restoring means fails to operate.

25. In a telephone exchange system, the combination of subscribers' calling lines, subscribers' called lines, automatic switch-

ing mechanism for interconnecting the lines including a connector switch, means for releasing said connector switch, and a special switch associated with the connector switch, 5 actuating means for said special switch, means controlled by the special switch for energizing the releasing means, and means for maintaining the operating means of the special switch active when the connector 10 switch fails to be released.

26. In a telephone exchange system, the combination of subscribers' calling lines, subscribers' called lines, automatic switching mechanism for interconnecting the lines including a connector switch, means for restoring the connector switch to disconnected position, a special automatic switch associated with the connector switch and having a normal position, means for rotating said special 15 switch, and means on said special switch whereby the releasing means for the connector switch is rendered active and the special switch is brought to rest at its normal position.

27. In a telephone exchange system, the combination of subscribers' calling lines, subscribers' wanted or called lines, automatic switching mechanism for interconnecting the lines including a connector switch, 20 means for releasing the connector switch when either the calling or called subscriber hangs up his receiver or in case the called subscriber does not answer, comprising a special switch adapted to be electrically connected with the connector switch, means for 25 operating said special switch, and means whereby said special switch and its operating means are maintained active in case the connector switch does not restore thereby 30 serving as a signal to an attendant.

28. In a telephone exchange system, the combination of calling lines, called or wanted lines including a party line, link circuits and automatic switching mechanism 45 for interconnecting the lines including a connector switch, means for releasing the connector switch controllable by either the calling or called subscriber or operative when the called subscriber fails to answer, 50 a special switch associated with the connector switch, means for rotating the special switch, party line selective ringing apparatus controlled by said special switch, means on the special switch, rendered active 55 when the connector switch fails to be released by the releasing means, for maintaining the rotating means of the special switch in operation so that the special switch will come to rest only at a predetermined position.

60. 29. In a telephone exchange system, the combination of calling lines, wanted or called lines, link circuits and automatic switching mechanism including a connector switch for interconnecting the lines, means

for releasing the connector switch, a special switch associated with the connector switch and having banks of contacts thereon, means for operating said special switch, ringing means associated with one of said banks of 70 contacts and adapted to be connected to the lines, said special switch having a normal position, an incomplete control circuit associated with the normal position and partly completed by said connector switch, means 75 for energizing the connector switch releasing the means, and means for maintaining the special switch in operation when the connector switch fails to release and break the control circuit associated with said normal 80 position.

30. In a telephone exchange system, the combination of calling and called or wanted lines, link circuits and automatic switching mechanism including a connector switch for 85 interconnecting the lines, a magnet for releasing the connector switch, a special switch associated with the connector switch having means thereon for connecting energy to said magnet, means for rotating the special switch, said special switch having a normal position, a control circuit for the rotating means associated with the normal position and rendered inactive when the connector switch is released but adapted to 90 maintain the rotating means in operation when the releasing magnet fails to operate or the connector switch fails to be released.

31. In a telephone exchange system, the combination of subscribers' calling lines, 100 subscribers' wanted or called lines including a party line, link circuits and automatic switching mechanism including a connector switch for interconnecting the lines, means for operating the connector switch, means 105

for releasing the connector switch, a special switch associated with the connector switch and having banks of contacts and contactors therefor, means for rotating said contactors over the banks of contacts, one of said banks 110 of contacts having selective ringing devices connected thereto, means for connecting either the tip or sleeve conductors to the ringing devices, banks of contacts of said special switch having a normal position 115 thereon, a circuit arranged to control the special switch rotating means associated with the normal position of one of said banks, and rendered partly complete when the connector switch is in connected position, a conductor connected to the releasing magnet and terminating in another bank of contacts, one of said contacts of the special switch being arranged to energize the releasing magnet after the switch has passed the 120 normal position, said rotating means being maintained in operation until the connector switch is restored to inoperative position.

32. In a telephone exchange system, the combination of a called subscriber's line, a 130

wanted subscriber's line, an operator's position to which said lines may be connected, means including selector and connector switches for extending connections between 5 the lines, a visual signal located at the operator's position, a test relay associated with the connector switch, means for operating said relay in case the wanted line is busy, means controlled directly through the contacts of said relay for immediately causing 10 the intermittent operation of said signal.

33. In a telephone exchange system, the combination with a manual board, calling subscribers' lines terminating in jacks therein, in a cord circuit having an answering and a calling plug, a calling supervisory signal associated with said cord circuit, a semi-automatic board, a trunk circuit terminating at one end in a jack at said manual board, 15 an automatic switch at said semi-automatic board, called subscribers' lines terminating in said switch, means for connecting said trunk to said switch, a sender at said semi-automatic board for setting said switch on 20 a called line, and means actuated by the busy condition of the called line to cause 25 said supervisory signal to be operated.

34. In a telephone system, a called line, an A-operator's board, a B-operator's board, 30 automatic switches controlled from said B-operator's board for extending connection to the called line, a signal on said A-operator's board, and means for operating said signal when said automatic switches attempt to 35 make connection with a busy line.

35. In a telephone system, a called line, an A-operator's board, a B-operator's board, automatic switches controlled from said B-operator's board for extending connection to 40 the called line, a visual signal on said A-operator's board, and means for intermittently operating said signal when said automatic switches attempt to make connection with a busy line.

36. In a telephone system, a called line, an A-operator's board, a B-operator's board, automatic switches controlled from said B-operator's board for extending connection to the called line, a supervisory signal on 45 said A-operator's board, means for operat-

ing said signal to indicate when a called subscriber responds and when a disconnection is desired, and means for operating said signal when said automatic switches attempt to make connection with a busy line. 55

37. In a telephone system, a called line, an A-operator's board, a B-operator's board, automatic switches controlled from said B-operator's board for extending connection to the called line, a supervisory signal on said 60 A-operator's board, means for operating said signal to indicate when a called subscriber responds and when a disconnection is desired, and means for intermittently operating said signal when said automatic 65 switches attempt to make connection with a busy line.

38. In a telephone exchange system, the combination of an operator's position, a signal at said position, wanted subscribers' 70 lines, means for establishing a connection from said position to a wanted line comprising a selector and connector switch, restoring means for said connector switch, a relay associated with said connector switch, means for operating said relay in case the wanted line is busy to cause the intermittent operation 75 of said signal and the operation of said restoring means.

39. A telephone system comprising a call 80 ing subscriber's and a called subscriber's line, means including an A-operator's link circuit, a B-operator's link circuit and an automatic switch for connecting said lines, an automatic machine-controlled impulse 85 sending device for controlling said switch, a supervisory signal for said A-operator's link circuit operated upon completion of the connection to the called subscriber's line, and means for intermittently operating said supervisory signal upon the completion of 90 said connection, if said called subscriber's line tests busy.

In testimony whereof I affix my signature in presence of two witnesses.

ARTHUR C. STUART
